EMPTY LOCK FOR VENDING MACHINES

Ernest H. Thompson, Winnetka, Ill.

Application April 13, 1940, Serial No. 329,436

5 Claims. (Cl. 194—1)

This invention relates to improvements in empty locks for vending machines and more particularly has to do with the provision of a finger disposed within a bin of bulk material in train with an external control whereby the finger will check for the presence of material in the bin upon each actuation of the external control.

One of the objects of this invention is to provide a new and improved empty lock for coin controlled machines for vending bulk material having a size capable of flowing, as for example peanuts, various types of hard surface candy and popcorn. In vending machines for this type of merchandise there is commonly a storage bin having at its base some form of measuring device such as a portioner in the form of a segmental wheel for dispensing a selected quantity of material upon each actuation of the dispensing means.

A second object of this invention is to provide a testing finger near the delivery station of the storage bin of a vending machine in train with an external control whereby each actuation of the external control will actuate the testing finger and will thereby serve to move it relative to the merchandise in the bin whereby it will check the presence of merchandise therein. As will more clearly appear hereafter, one of the features of this invention is the provision of a pivoted rigid wire at the bottom of a storage bin which wire is adapted to be moved through the merchandise in the lower portion of the bin upon each actuation of the external control and which wire in certain positions controls the passage of a coin through the coin mechanism.

A further object of this invention is to provide a stroke to the testing finger of such a length that the finger will not be able to act as a bridge to support the merchandise above it and thereby defeat its own purpose. It will be appreciated that a testing finger mounted near the delivery station within and at the bottom of a storage bin is surrounded by merchandise. It is supported by the merchandise below and pressed down by the merchandise above. In a machine where the testing finger of the empty lock is to be held in ineffective position when supported by merchandise beneath it, it is evident that the testing finger must not act as a bridge to support the merchandise above it, for under such circumstances the merchandise above would ultimately press the testing finger downwardly and lock the coin mechanism although the bin in fact were full. For this reason it is essential that the upward stroke of the testing finger in response to

the external control must be sufficiently great to cause some of the merchandise above to drop below the testing finger.

A further object of this invention is to make the testing finger of a size which offers as little resistance to the descent of merchandise around it as is possible without rendering the testing finger ineffective for its purpose.

A further object of this invention is to provide such an empty lock for use with either a free full stroke or a free partial stroke coin mechanism.

These and such other objects as may herein-after appear are attained by the embodiments illustrating the invention and shown in the drawings, comprising three sheets, wherein:

Figure 1 is a side elevation of a portion of a nut vending machine showing the external control lever and an empty lock testing finger in conjunction with a coin mechanism;

Figure 2 is a rear view in elevation, partly cut away, of the empty lock;

Figure 3 is a plan view showing the testing finger in a magazine; and

Figures 4 and 5 show a modified form of empty lock in association with a free partial stroke coin mechanism in a popcorn machine, Figure 5 being a view taken on the line 5—5 of Figure 4.

One embodiment of this invention is seen in Figures 1, 2 and 3 of the drawings where an empty lock is mounted in association with a coin controlled vending machine for dispensing nuts, such as peanuts. Only a comparatively small part of this vending machine is shown. Referring to Figure 1, a frame member 10 constitutes the framework of a coin mechanism 12 and the supporting means for a nut dispensing device 14, the details of which are not shown. A tubular container 16 (cut away between the lines 18 so as to permit the working parts of the empty lock to be seen) is seated on the nut dispensing holder 14 at 20, and more particularly, referring to Figure 3, rests on an inner shoulder 22 so as to form a storage bin for bulk material. The external control 24, which is formed integral with an arm 26 pivoted at 28, actuates the dispensing device 14 through the link 30 and other mechanism not shown.

The coin mechanism 12 may be of a variety of types. As shown in Figure 1, it includes a coin receiving slot 32 and a track which moves the coin along the dotted line 34 till it rests in the holder 36 of a weighing scale 38 pivoted at 40 and carrying an adjustable counterweight 42. A coin so held is shown in the position 44. At the end of 50 the coin path as indicated by the dotted line 34

the track is divided into two paths, one leading to a return cup and the other to a mechanism which, upon receipt of a coin, will enable movement of the control 24 to actuate the dispensing means 15. A coin traveling in a normal path will reach the position 44 and overcome the counter-weight 42 so that the scale 38 will assume the dotted position 46 whereupon it will drop the coin from the holding member 36 and the coin will continue downwardly to a position where it may be used by the lever arm 26 to effect actuation of the nut dispensing mechanism 14. When the scale 38 drops into the position 46 it will be observed that a scavenger 48 drops into the position shown by the dotted line 50 whereby the normal path will be closed and any coin not deposited in the slot 32 will be deflected to the other path and be returned to a coin cup available to the customer and not here shown.

The empty lock which is the subject of this invention comprises three movable members; namely, an L-shaped member 52, see Figure 1, an arm 54 having a camming surface or shoulder 56, see Figure 2, and a testing finger 58, see Figure 1. Of these three elements, the L-shaped member 52, the arm 54, and the testing finger 58, only the testing finger will be common to all applications of this invention, for the L-shaped member 52 and the arm 54 are shaped as they are only for the purpose of establishing a cooperative relationship between the testing finger 58 and the driving arm 26 on the one hand and the testing finger 58 and the scale 38 of the coin mechanism on the other. As will more clearly appear in the description of the second embodiment of this invention shown in Figure 4, it may be desirable to have the testing finger block actuation of the external control instead of functioning through the coin mechanism. It will be appreciated in the present embodiment of the invention that the empty lock need not act through the weighing scale of the coin mechanism but may be coupled to any scavenger in the coin mechanism.

Resuming the description of the particular embodiment shown in Figures 1, 2 and 3, the L-shaped member 52 is pivotally fastened to the driving arm 26 at 60 and is caused to move in a substantially vertical reciprocating fashion due to actuation of the external control 24 by means of the slot 62 riding a stud member 64 mounted in the frame 10. At the outer end of the L-shaped member 52 is a downwardly directed projection 66 which in turn is bent to form an inwardly directed projection 68. Referring to Figure 2, it will be observed that a second projection 70 is bent outwardly from the L-shaped member 52. Between these two projections 68 and 70 is positioned the arm 54 which is keyed to the shaft 72 which is keyed to the testing finger 58. Referring to Figure 2, a spring 74 having opposite ends 76 and 78 urges the arm 54 upwardly and the testing finger 58 downwardly. As shown in Figures 1 and 2 it will be noted that the arm 54 is held in the position shown against the pressure of the spring 74 by reason of the fact that the testing finger 58 is supported by the nuts 80. This position will hereinafter be referred to as the normal position for the testing finger because in operation for most of the time there are nuts or other vendible material in the bin and the testing finger occupies the position shown.

When the testing finger 58 is in normal position, referring to Figure 2, the tip 82 of the arm 54 does not engage the counterweight 42 of the

scale 38 but leaves the scale in the position shown in full lines, in Figure 1 so that upon the depositing of a coin in the coin mechanism 12 by a customer, the holding portion 36 of the scale 38 will receive the coin and drop it through position 46, and thereby permit the machine to function. Moreover, actuation of the lever 26 throughout the whole of its stroke will not cause the arm 54 to engage the scale 38 for the reason that on a downward motion of the external control 24, the arm 26 and the L-shaped member 52 move downwardly and the projection 70, see Figure 2, engages the camming surface 56 of the arm 54 and moves the end 82 away from the counter-weight 42. The effect of this arrangement is to cause the testing finger 58 to rise to the dotted position 84. When the lever 26 returns from actuated position 86 to its original position, the testing finger 58 will be forced downwardly through the nuts by means of the projection 68. Actuation of the lever 26, therefore, when there are nuts in the position 80, will cause the testing finger 58 to rise to position 84 and back to normal without interfering in any way with the operation of the scale 38.

In the event, however, that the level of the nuts should fall sufficiently low to permit the testing finger to assume the position 88, see Figures 1 and 2, the arm 54, which is free to move between the projections 68 and 70, will move into the position 90 and engage the counterweight 42. The spacing of the projections 68 and 70 is such that the spring 74 will be able to tip the scale counter-clockwise so that it occupies the position 92, see Figure 1. In this position the scavenger 48 will drop into the position 50, heretofore mentioned, and any coin which descends the coin track will be rejected by the scavenger 48 and returned to the customer.

Summarizing the operation of this empty lock in association with a free full stroke coin operated vending machine, a patron without inserting a coin into the slot 32 may move the external control 24 to the position 86 freely and in so doing he will cause the testing finger 58 to move upwardly, see Figure 1, to position 84 and upon the return of the external control 24 to its original position, the testing finger 58 will be returned to its normal position. These movements will not affect the position of the scale 38 which will continue ready to receive a coin. If the customer now drops a coin into the slot 32, the holding member 36 of the scale 38 will receive it and moving down to position 46 will cause the coin to move into an accepted position, not shown, where actuation of the external control 24 will cause the machine to deliver merchandise.

If, however, the level of the merchandise in the bin 16 has dropped to a point such that the testing finger 58 will cause the end 82, see Figure 2, of the arm 54 to engage the counterweight 42, the holding member 36 of the scale 38, see Figure 1, will drop into position 92, thereby dropping the scavenger 48 into position 50 so that any coin dropped by a customer will be returned to the customer.

It will be observed that the testing finger 58 is merely a fairly heavy wire. It has been found that the use of a finger presenting a greater area to the merchandise in the bin will not do the work more effectively and will assist in building up bridges in the bin which frequently force the testing finger 58 downwardly to position 88 and render the machine inoperative although there is ample merchandise in the bin.

Attention is also invited to the relationship of the distance between the normal position and position 84 and the size of the nuts 80. It is desirable that the testing finger 58 be moved upwardly on each cycle of the machine by a distance greater than the diameter of the particular particles which are being dispensed, for otherwise the testing arm might assist in building up a bridge of the articles in the bin. If, for example, the particular bin shown was filled with popcorn, the upward stroke of the testing finger shown in this embodiment would not be sufficiently great to penetrate the popcorn and permit the latter to drop below the testing finger. The length of the stroke, therefore, is important.

A second embodiment of this invention is shown in Figures 4 and 5 and is characterized by the fact that the coin mechanism 100, shown in Figure 4, is of a type which will permit a free partial stroke of the link 102 as contrasted to the free full stroke permitted by the coin mechanism shown in the first embodiment. Describing briefly the structure shown in these two figures, 104 is the cabinet of a popcorn machine having a bin 106 with bottom walls 108 sloping into a delivery orifice 110. The portioning chamber and dispensing devices are not shown, but they are actuated by a master shaft 112 to which is keyed the external control knob 114 on the arm 116. An arm member 118 is keyed to one end of the jack shaft 112, see Figure 4, and is connected to the link 102 by the pin 120. The arm 118 has two projections 122 and 124 in alignment with an arm 126 pivoted at 128 and extending into the delivery passageway 110 as the testing finger 130.

The coin mechanism 100, being of the free partial stroke type, will permit a downward movement of the knob 114 and the arm 116 to the dotted position indicated by the numeral 132 in Figure 5. No further movement of the external control knob 114 or of the jack shaft 112 or of the link 102 will be permitted unless an acceptable coin has reached an accepted position in the coin mechanism 100, although there is frequently interposed between the arm 116 and the jack shaft 112 a heavy spring which will permit further actuation of the external control knob 114 while the jack shaft 112 remains motionless in order to prevent a customer's damaging the machine by attempting to force the external control knob 114. This free movement of the external control 114 between the normal position shown in Figure 5 to the dotted position 132 is possible at all times. It will be observed that the arm 118 will assume the dotted position 134 on such a movement.

When an acceptable coin has been introduced to the coin mechanism 100, the coin mechanism will release the link 102, thereby permitting the customer to press downwardly the external control knob 114 to the dotted position 136, under which circumstances the arm 118 will assume the dotted position 138. It will be noted that during this movement of the arm 118, the arm 126 of the testing finger 130 has not interfered therewith for the popcorn at position 140 is supporting the testing finger and the popcorn is not released from whatever type of portioning chamber is used until after the projecting member 124 has passed the tip of the arm 126. It will be appreciated that this last statement about the time of the delivery of the popcorn is of necessity true in a free partial stroke coin mechanism vending

machine because no popcorn is to be delivered during the free partial stroke.

If there is no corn in position 140 the testing finger will occupy position 142 and the arm 126 will occupy the dotted position 144 with the result that as the arm 118 moves upward the arm 126 moves into position to engage the projecting member 124 and to prevent further downward movement of the external control knob 114. The operation of this testing finger differs from the operation in the first embodiment of the invention in that here the testing finger blocks further actuation of the external control, whereas in the first embodiment disclosed above, the testing finger blocks acceptance of a coin in the coin mechanism. In machines employing an empty lock in conjunction with a free partial stroke coin mechanism where an acceptable coin has reached accepted position in the coin mechanism, the coin is returned to the patron by means of a scavenger flicked by any back stroke of the link 102, see Figure 4, and hence of the external control knob 114.

Describing the steps of the movements of the empty lock through the ordinary cycling of the machine when an acceptable coin is placed in the coin mechanism 100 and an adequate supply of popcorn is in the bin 106, the external control knob 114 will be moved downwardly until the projecting member 124 is opposite the end of the arm 126, which is indicated by the dotted line position 134 of the arm 118. Inasmuch as the coin mechanism permits further movement of the link 102 and the external control knob 114, the downward movement of the knob may be continued under which circumstances the arm 118 will move toward the position 138. In doing so there ordinarily will simultaneously occur a flow of corn through the delivery opening 110 from the bin 106 and this will cause the testing finger 130 to move into position 146 and the arm 126 to move into the position 148. On the return of the external control knob 114 to normal the projecting members 124 and 122 of the arm 118 will return the arm 126 and the testing finger 130 to their normal positions.

As will be apparent by reference to the foregoing discussion, coin mechanisms for machines of the type described may be divided into two classes depending upon the length of the free stroke permitted to the external control. Thus, some coin mechanisms are so designed and coupled with the vending machine that a manual external control may be fully actuated at all times regardless of the passage of a coin through a coin mechanism. If no coin has passed through the coin mechanism, the machine will deliver nothing although the external control be fully actuated. The embodiment of the invention illustrated in Figures 1 to 3 is of this type.

The second class of machines are those having a coin mechanism which will permit a free partial stroke of the external control. These coin mechanisms are directly coupled to the external control and upon actuation of the external control will, if no acceptable coin has passed through the coin mechanism, stop actuation of the external control mechanically. On a return of the external control to normal position, the return stroke will flick an ejector mounted at the accepted coin position of the coin mechanism, and return to the customer an accepted coin. It will be appreciated that a testing finger actuated by a free full stroke external control will test the presence of merchandise in a storage bin upon

actuation of that control regardless of the delivery of merchandise by the machine, whereas a testing finger responsive to the external control of a free partial stroke machine will test the presence of goods in a bin on each movement of the external control if the testing finger is actuated during the partial stroke. But, if the testing finger is actuated only during the operating part of the stroke of the external control, then the testing finger will check the presence of corn in the bin only when the machine goes through a delivery cycle. In the second embodiment of this invention, the testing finger checks the presence of corn in the bin on the return full stroke of the external control.

It will, of course, be appreciated that this invention may be adapted to vending machines which are electrically operated. In such machines the external control usually consists of a button or in some instances the mere depositing of a coin will cause the machine to go through one dispensing cycle. Under such circumstances the testing finger such as 58, see Figure 1, will be actuated by any force available in the machine to cause the cycling thereof and when a bin has become nearly empty, the testing finger may cause a scavenger finger to enter a coin track and prevent the acceptance of coins by the coin mechanism.

It will be understood that the external control is made effective to actuate the dispensing means by a suitable coin control mechanism, such as for example, the coin mechanism disclosed in U. S. patents, Re. 21,451 and 2,251,994. As already indicated, the coin mechanism may be one in which the external control has a free full stroke or a free partial stroke.

Numerous other changes may be made in the apparatus described without departing from the invention.

Having thus described my invention, what I claim as new and desire to secure by Letters Patent of the United States is:

1. An empty lock for a vending machine comprising a storage bin for bulk material, means for rendering the machine inoperative, a rigid wire shaft horizontally journaled at one side of said storage bin and having an extension within the storage bin bent out of alignment with the axis of the shaft whereby said extension is responsive to the absence of bulk material in the bin and an oscillatory movement thereof will cause a rotation of said shaft, and a train of members extending between said shaft and said first named means so arranged that movement of said extension due to absence of bulk material in said bin will result in actuation of said first named means.

2. In a vending machine having a storage bin for bulk material, an external control, a coin mechanism adapted to receive a coin to render the vending machine operative upon actuation of said external control, the combination of a testing finger within the storage bin normally embedded in the bulk material and supported thereby at a substantially predetermined level, elevat-

ing means responsive to the actuation of said external control to cause said testing finger to be positively raised through said bulk material during a vending operation when said bulk material is above said predetermined level, means to reset said finger to said predetermined level, and means operatively associated with said testing finger and with said coin mechanism to prevent a coin from being accepted by said coin mechanism when said finger on being reset drops below said predetermined level.

3. An empty lock for a vending machine having a storage bin for bulk material and an external control, comprising testing means in said bin normally supported by said bulk material and adapted to drop to a selected position unless a predetermined amount of said supporting material is present, said testing means also being adapted to be raised to a level above its normal position, means operatively associated with said external control and with said testing means for positively raising said testing means in a direction opposed to the flow of said bulk material during each vending operation, means to restore said testing means substantially to its normal position by the end of a vending operation provided a sufficient quantity of said bulk material is present to maintain it in said position, and means operatively associated with said testing means for rendering said vending machine inoperative when the amount of said bulk material is such that the testing means drops to said selected position.

4. In a vending machine having a storage bin for bulk material and an external control, testing means normally embedded in said bulk material, said testing means being adapted to move to a selected level when said bulk material in said bin drops below a predetermined level, means operatively associated with said testing means for rendering said vending machine inoperative when the amount of said bulk material is such that the testing means is arrested at said selected position, and means responsive to the movement of said external control to positively raise said testing means in a direction opposed to the flow of said bulk material during each vending operation.

5. In a vending machine having a storage bin for bulk material, an external control capable of a free partial stroke at all times, and a coin mechanism adapted to receive a coin to render the vending machine operative, the combination of a testing finger normally embedded in the bulk material at a predetermined level, said testing finger being biased to drop by gravity, means operatively associated with said testing finger and said external control for blocking the full stroke of said external control when said testing finger drops and is arrested at a selected position due to the absence of said bulk material at said predetermined level, and elevating means responsive to the operation of said external control for positively raising said testing finger to its original position during a vending operation.

ERNEST H. THOMPSON.

CERTIFICATE OF CORRECTION.

Patent No. 2,383,229.

August 21, 1945.

ERNEST H. THOMPSON.

It is hereby certified that error appears in the printed specification of the above numbered patent requiring correction as follows: Page 2, first column, line 16, for the word "not" read --now--; and that the said Letters Patent should be read with this correction therein that the same may conform to the record of the case in the Patent Office.

Signed and sealed this 25th day of December, A. D. 1945.
